UNITED STATES PATENT OFFICE.

JOHN OWENS, OF KINGSTON, IOWA.

GASOLENE-LAMP.

1,234,796.

Specification of Letters Patent. Patented July 31, 1917.

Application filed December 8, 1916. Serial No. 135,774.

To all whom it may concern:

Be it known that I, JOHN OWENS, a citizen of the United States, and a resident of Kingston, in the county of Des Moines and 5 State of Iowa, have invented a certain new and useful Improvement in Gasolene-Lamps, of which the following is a specification.

My present invention relates generally to 10 gasolene lamps, and more particularly to the general construction thereof, as utilized in connection with either gravity feed or force feed gasolene lighting systems.

The primary object of my present improvement is to provide a gasolene lamp, the construction, connection, and coöperative action of the several parts thereof being such as to not only permit of installation of the lamp in the first instance, but the detachment, repair or substitution of any one 20 or more of its several parts in a ready, quick, and convenient manner without the necessity of skilled labor or the use of special tools and implements for this purpose.

As is well known, the gasolene lamps now in use are of a complicated construction such 25 that, when the parts thereof become worn, broken, or disarranged, it is necessary for the user to purchase an entirely new lamp, occasioning unwarranted expense and delay and work, and usually requiring the services of a skilled mechanic for both the removal of the old lamp and the installation of the new one.

With my present invention these disadvantages may be overcome and the foregoing objects carried out, as plainly to be seen from the following description of the construction, combination, and operation of its 40 several parts, reference being had to the accompanying drawings which illustrate the invention and form a part of this specification.

In the drawings:

Figure 1 is a side view partly in elevation and partly broken away and in section, illustrating the complete lamp as proposed by my invention;

Fig. 2 is a horizontal section taken there- 50 through, substantially on line 2—2 of Fig. 1;

Fig. 3 is a detail perspective view enlarged of the upper portion of the lamp, adjacent the hanger casting;

Fig. 4 is a vertical sectional view through 55 the lower central portion of the lamp;

Fig. 5 is a similar view taken substantially on line 5—5 of Fig. 4;

Fig. 6 is a side view of the lower central portion of the lamp;

Fig. 7 is a detail sectional view illustrating 60 a slightly modified form of lamp, and

Fig. 8 is a similar view taken substantially on line 8—8 of Fig. 7.

Referring now to these figures, the lamp 65 as proposed by my invention is suspended from a suitable support by means of a hanger pipe 10, as seen best in Figs. 1 and 3, downwardly through which extends the gasolene branch 11 from the gasolene feed 70 pipe, which as well known, leads from a supply tank either by gravity where the tank is elevated, or by force feed in connection with a low-down tank.

The lower end of the hanger pipe 10 is 75 securely fastened to the upper portion of a hanger casting 12 having a lower angular portion 13 to which the upper offset extremities 14 of the lamp frame 15 are secured by a bolt or suitable fastening member 16, the 80 lower end of the gasolene branch 11 being detachably connected by a connecting pipe 17 adjacent the casting 12 to the upper end of a lamp tube 18 carried by one of the side extensions of the frame 15, in a manner to 85 be presently described.

The frame 15, as seen in Fig. 1, is preferably in a single piece, being bent to the form shown from a rod, the intermediate portion 19 of which at the base of the lamp 90 is flattened and one side of which is longitudinally grooved to receive the lamp tube 18 in the groove thereof, so that the latter will at all times be within the sight and reach of the user of the lamp, in order that 95 any leak may be readily and quickly detected and as readily and as quickly repaired, the upper end of such tube being detachable, as previously described, and the lower end thereof being detachably connected by similar means to the controlling member 20.

The member 20 is secured in vertical position to the intermediate flattened portion 19 of the lamp frame, by means of screws or other detachable fastening members 21, ex- 105 tending through its side ears 22 and through the portion 19 of the frame, the upper end of the feed member 20 projecting within the

flattened portion 19 of the frame serving as a support for a collar 23 from which the radially shaped supporting arms 24 extend in order to receive and effectively support a shade 25 of suitable form, as for instance that shown in Fig. 1.

The feed controlling member 20 is also provided with a vertical bore 26, the lower end of which communicates with the lateral bore 27 to which the lower end of the tube 18 is connected, through a port 28 controlled by a needle valve 29, the upper portion of the depending stem 30 of which is threaded into the lower portion of the feed member 20, so that the stem may be turned by its lower key 31 to control the feed of gasoline from the lower end of the tube 18, upwardly through the vertical bore 26, the feed member 21 having a lateral bore projecting in the opposite direction from that of the bore 27, and normally closed by a plug 32 by means of which the feed member may be thoroughly cleaned when desired.

Thus it will be noted that the bore 26 is out of alignment with the needle valve 29, so that pressure cannot act directly in the length of the latter and thus endanger leakage past its threaded portion within the said feed member.

It is also obvious from the construction of the feed controlling member 20 that this portion of the lamp may be readily detached by releasing the screws 21, for repair or substitution, and that this construction permits of cleaning whenever necessary or desirable.

Upstanding above and at one side of the feed controlling member 20 is a gas feeding member 33 having lower laterally projecting ears 34 connected by screws or like fastening members 35 to the flattened portion 19 of the frame and having a bore 36, the lower portion of which is threaded for the reception of a threaded stem 37, the lower end of which projects below the frame portion 19 exteriorly of the member 33, and is provided with a key 38.

The gas feed member 33 is also provided adjacent its upper end with a laterally opening nipple 39 to which is detachably connected one end of a vaporizing pipe 40, the opposite end of which is similarly connected to the upper end of the feed controlling member 20, as particularly seen in Fig. 4, the outer extremity of the gas feeding member 33 being provided with a conical opening into which a conical spray plug 41 extends, this spray plug being held in detachable connection with the upper end of the member 33 by means of a gasket nut 42 and having a minute opening through which the gas is sprayed upwardly into the burner pipe 43, the lower portion 44 of the latter of which telescopes upon the upper end of the member 33.

The burner pipe, of an unthreaded U-

shape and of either the double form shown at 43 in Figs. 4 and 5, or the single form, as shown at 43^a in Fig. 6, has a laterally extending air intake nipple 45 extending in a direction opposite to the burner 46, so that the gas sprayed through the spray plug 41 will draw in its charge of air and intermix therewith during its passage through the pipe to the burner 46 and at the same time the flame from the burner will be prevented from blowing over the spray plug 41.

The burners 46 support incandescent mantles of the inverted U-type, as indicated in dotted lines at 47 in Figs. 4, 5, and 6.

The upper end of the stem 37 within the gas feed member 33 is provided with a needle 48 which, by turning the stem 37 to move the same upwardly, may be projected into and through the minute opening of the spray plug 41 to clean the same should it become wholly or partially clogged, reverse movement of the stem serving to withdraw the needle to its normal position below the spray plug, and permit free passage of the gas through the plug.

It is obvious from the foregoing that the construction and arrangement of the parts as previously described, permits of freely removing the burner pipe 43 or 43^a, and the removal of the spray plug 41 for repair or substitution, by unscrewing the gasket nut 42, although the needle 48 at the other end of the stem 37, actuated in its movements by manipulation of the lower key 38, will serve to dislodge any undesirable accumulation within the minute opening of the plug and maintain the latter in cleanly condition. As sometimes happens, however, the accumulation within the opening of the plug is such as to prevent movement of the needle through the same, and even break the needle off, and in such case removal of the plug and insertion of a new one, which can be readily accomplished by the construction provided by my invention, is greatly to be desired.

It is to be observed, furthermore, that either the feed controlling member 20 or the gas feed member 33 may be independently removed, the vaporizing pipe 40 being detachable from either or both thereof, so that these parts may be independently renewed or repaired without disturbing the remaining parts.

It is further to be observed that the detachable connections of the tube 18 and the vaporizing pipe 40 including a cone at the ends of the pipes held in position within a conical seat in the connecting members, as seen at 49 in Fig. 4 in particular by means of a gasket nut 50, may be modified as to the gasket nut 50 as seen in Figs. 7 and 8, by the substitution therefor of a yoke 51, as seen in the latter figures, to engage the cone 49 and force the same into position under pressure exerted by a thumb screw 52 threaded

through the yoke, thus avoiding the necessity of threaded engaging parts and the danger of crossing the threads in the hands of unskilled inefficient operators.

5 In addition to the foregoing advantages, the construction as proposed by my invention is not only more simple but is considerably cheaper and otherwise more efficient than the constructions heretofore utilized.

10 I claim:—

1. A gasoline lamp comprising a frame consisting of a single piece having its lower portion disposed horizontal and having its extremities bent upwardly and angularly in 15 opposing relation, a hanger casting to which the said upper extremities of the frame are secured, one side of the extension of the frame having a groove longitudinally along its outer surface, a gasoline feed pipe extending into the said groove, and gasoline vaporizing and burning elements detachably connected to the lower horizontal portion of the frame and with which the lower end of the said gasoline pipe communicates.

25 2. A gasoline lamp comprising a frame in one piece, having the free ends thereof bent upwardly adjacent to one another, a hanger to which the said upper free ends of the frame are secured, a branch gasoline pipe 30 depending into the said hanger, one of the side portions of the frame having a lengthwise groove, a gasoline feed pipe extending along the said side portion of the frame and disposed in the groove thereof, gasoline vaporizing and burning means carried by the 35 lower portion of the frame, and detachable connection between the said feed pipe and the said gasoline branch and the said vaporizing and burning means whereby the feed 40 pipe may be bodily removed.

3. A gasoline lamp comprising a frame, a burner pipe, a gas feeding member having a spray plug opening into the burner pipe, a gasoline feed member having feed

controlling means, means detachably connecting said gas feeding member and said gasoline feed member to the said frame independently of one another, and a vaporizing pipe detachably connected to said gasoline feed member and to said gas feed member and communicating therebetween.

4. A gasoline lamp comprising a frame, a feed controlling member, a gas feeding member, means for detachably connecting said members directly to said frame independently of one another, a vaporizing pipe detachably connecting the said members, and a burner pipe in communication with said gas feeding member.

5. A gasoline lamp comprising a frame, a portion of which is provided with an external longitudinal groove, a gasoline branch at the upper portion of the frame, a feed member at the lower portion of the frame, and a feed pipe extending within the groove 65 of the frame, and detachably connected at its upper and lower ends with said gasoline branch and the said feed member.

6. In a lamp of the character described, the combination of a frame having a lower 70 flattened portion, a gasoline controlling member, a gas feeding member, means for detachably connecting said members upon the flattened portion of the frame, a vaporizing pipe connecting the said members, and 75 a burner pipe detachably supported upon the said gas feeding member.

7. In a lamp of the character described, the combination of a support, gasoline controlling and gas feeding members independently and detachably connected directly to the support, a burner pipe detachably supported upon said gas feeding member, and a relatively small generator tube detachably connected at one end to said gasoline controlling member and at its other end to the said gas feeding member.

JOHN OWENS.
